UNITED STATES PATENT OFFICE.

RAYMOND M. HOOD, OF NEW YORK, N. Y., AND WALLACE F. GOODNOW, OF GREENWICH, CONNECTICUT, ASSIGNORS OF ONE-THIRD TO PLACIDO MORI, OF NEW YORK, N. Y.

RADIATOR.

1,411,659.

Specification of Letters Patent.

Patented Apr. 4, 1922.

Application filed July 25, 1919. Serial No. 313,347.

To all whom it may concern:

Be it known that we, RAYMOND M. Hood, a citizen of the United States, residing in the borough of Manhattan, city, county, and 5 State of New York, and WALLACE F. Goodnow, a citizen of the United States, residing at Greenwich, county of Fairfield, State of Connecticut, have invented certain new and useful Improvements in Radiators, of 10 which the following is a specification.

The present invention relates to radiators and has for an object to provide an improved radiator which may be set into the wall in a dwelling or other building, which 15 will be attractive in appearance and will efficiently provide heating surface. The invention will be better understood by reference to the accompanying drawings forming part hereof in which is shown a selected 20 embodiment of the invention and in which

Figure 1 is a rear elevation of a radiator constructed in accordance with the invention.

Fig. 2 is a sectional view taken on the line 25 2-2 of Fig. 1.
Fig. 3 is a sectional view, similar to Fig. 2, showing a modification of the form of radiator illustrated in the other figures.
In accordance with the invention, the 30 front face of the radiator constitutes the front face of a heating section and is designed to afford a surface of pleasing appearance which may be set substantially flush with the face of the wall and form a 35 part thereof. Such radiator face can be of such color and design as will best adapt it to the decorative scheme of the room.

The radiator is designed to be used with any suitable heating medium such as, for 40 example, steam or hot water, but for convenience will hereafter be described as designed for use with steam.

In the embodiment illustrated, the radiator consists of two heating sections or units 45 1 and 2 suitably connected together and provided with an inlet connection 4, an outlet connection 5, and an air vent 6. Suitable means for supporting the radiator in position while permitting circulation of the 50 air of the room or air introduced from behind the radiator, is afforded by a flange 8 which, as shown, extends from the top, bottom and both sides in the plane of the front face of the front section forming in

effect a continuation of such front face. By 55 such construction the radiator unit is in direct contact with the air of the room and furthermore radiates directly into the room, avoiding obstruction of radiation by the employment of an auxiliary screen designed 60 to cover and protect the radiator.

At the top and bottom, the flange 8 is provided with openings 10 and 11 which permit desired circulation. The natural upward current of heated air behind and between the heating sections, causes sufficient circulation. Ordinarily, it is unnecessary to provide means to close these openings. In the illustrated embodiment, a shield 14 is provided which confines the air to prevent waste of heat into the wall. Such shield is secured in place in a suitable recess in the wall and affords a convenient support to which to secure the radiator. As shown, a skeleton plate 16 has secured thereto a plurality of brackets 17, 17, which receive the edge of the flange 8 to support the radiator and which fit within the shield as shown in the drawing. The plate 16 may further be secured in place in any suitable way. 80

The heating sections may be connected together in any suitable way. As shown, each section is provided with pipe fittings 18, 18, secured in place and threaded nipples 20 of a type well known in the art are used to connect the same, all as will be clear to one skilled in the art. Similar fittings upon the rear face of the rear section serve as steam inlet and outlet connections. 85

The radiator is preferably made by electrodeposition of copper on a celluloid shell. In the construction shown, a shell 22 of celluloid is made to conform to the desired shape of a finished radiator section and then electroplated with a sufficiently thick deposit of copper 23 to provide a shell of the desired strength and rigidity. Suitable fittings are secured in position upon the celluloid shell and when the electroplating is accomplished said fittings are rigidly secured 100 in place and form, in fact, an integral part of the radiator construction, as shown in section in Fig. 2. The method of manufacture of the section 2 is the same as above described but the shape of the shell is different because of the omission of the flange 8. 105

After the celluloid has served its purpose,

it can advantageously be removed for re-use by a suitable solvent.

The removal by the solvent has also the advantage that the flange 8 is thereby made 5 hollow to receive steam and thereby constitutes an extension of the heating member providing a very substantial additional heating surface. If celluloid of sufficient thickness is used in the construction of the 10 shell 22, especially the flange, it is unnecessary to resort to other expedients to thicken the flange to make space therein of sufficient dimensions to avoid the choking by condensation. The flange at the top and both sides 15 thus becomes effective as an extension of the heating surface even without the provision of additional means for draining water therefrom. The portion of the flange which extends downwardly would hardly be available 20 as a heating surface because it would soon become filled with condensed steam unless provision is made for draining the steam therefrom at the bottom or unless the outlet were made to extend from the bottom 25 portion of said flange instead of from the body of the heating unit, as shown.

In Fig. 3 is shown another radiator embodying the invention in which a differently shaped but equivalent construction is illustrated. In Fig. 3 the heating sections 25, 30 26, have parallel front and back walls extending the full length of the sections and ventilation is provided by holes 27, 27, extending horizontally through the sections 35 near the top and bottom. The walls of the ventilating holes may be formed by electro-deposition or, if desired, may be formed by introducing previously prepared square tubes into the celluloid form before electro-plating. The arrangement of the tubes is 40 substantially the same as the arrangement of the ventilating openings 10, 10, in the construction shown in Figs. 1 and 2 except that four of the lower tubes are omitted to

provide a suitable place for attachment for 45 the lower fittings 28, 28, which are thus positioned lower than in the construction shown in Figs. 1 and 2, to provide proper circulation of steam and prevent a water pocket.

The sections are supported in suitable 50 brackets, 29, 29, engaging the edges of the sections and suitably supported.

Obviously, modification in the structural details and in the method of manufacture of the device may be made within the scope 55 of the invention.

I claim:

1. A radiator of the character described having a plurality of parallel thin flat fluid-receiving heating units rigidly connected together, the front unit having a supporting flange extending outwardly therefrom in the plane of the front face of said heating unit and forming in effect a continuation of said front face. 60

2. A radiator of the character described having a thin flat fluid-receiving heating unit provided with a supporting flange extending from said unit in the plane of the front face thereof, said supporting flange 70 being hollow to receive heating fluid and constituting an extension of said heating unit.

3. A radiator of the character described comprising a thin flat fluid-receiving heating unit presenting a substantially continuous flat heating surface and having near its upper and lower edges ventilating tubes extending through the unit from face to face thereof, and means for supporting such 80 heating unit within a recess in a wall with one face substantially flush with the wall. 75

June 27, 1919.

In testimony whereof we have hereunto set our hands.

RAYMOND M. HOOD.
WALLACE F. GOODNOW.
